CLAIM

The ornamental design for a bowl for an ice cream maker as shown and described.

DESCRIPTION

FIG. 1 is a perspective view of a bowl for an ice cream maker according to the design;

FIG. 2 is a front elevation view thereof, a back elevation view thereof being identical to the front elevation view;

FIG. 3 is a right side elevation view thereof, a left side elevation view thereof being identical to the right side elevation view;

FIG. 4 is a top plan view thereof;

FIG. 5 is a bottom plan view thereof; and,

FIG. 6 is a perspective view of the bowl for an ice cream maker of FIG. 1 shown assembled with a stand mixer in connection with an ice cream maker attachment, therefore. Dash-dot-dot-dash broken lines are environmental only and form no part of the claimed design.

The portions of the article shown in even broken line form no part of the claimed design.

Dash-dot-dash broken lines adjacent un-shaded areas represent bounds of the claimed design and form no part of the claimed design themselves.
